UNITED STATES PATENT OFFICE.

FREDERICK R. HAWLEY, OF SYRACUSE, NEW YORK.

BARK-ROSSING MACHINE.

1,043,829.

Specification of Letters Patent. Patented Nov. 12, 1912.

Application filed March 18, 1910. Serial No. 550,270.

To all whom it may concern:

Be it known that I, FREDERICK R. HAWLEY, of Syracuse, in the county of Onondaga and State of New York, have invented a 5 certain new and useful Bark-Rossing Machine, of which the following is a specification.

My invention has for its object the production of a particularly simple and efficient 10 machine for rossing bark, and it consists in the combinations and constructions herein-after set forth and claimed.

In describing this invention, reference is had to the accompanying drawing, in which 15 like characters designate corresponding parts in all the views.

Figure 1 is a side elevation, partly in section, of one embodiment of my bark rossing machine. Fig. 2 is a front elevation thereof, 20 parts being omitted. Fig. 3 is a sectional view illustrative of the manner of mounting the sheaves on their supporting shaft. Fig. 4 is a sectional view of the lower pressure means of this bark rossing machine, and 25 contiguous parts. Fig. 5 is a sectional view of the abrading member and deflector, and contiguous parts. Fig. 6 is a section on line A—A, Fig. 5.

My bark rossing machine comprises, generally, belt members provided with lengthwise sections and having portions opposed to each other, the space between said opposed portions forming a passage for the branches, the bark of which is to be rossed, 30 means for actuating the belt members, and means for stripping the loosened bark from the branches.

1, 1 are angle iron side elements of the frame of this machine, and 2, 2 are legs for 40 said elements.

3, 4 are belt members having portions opposed to each other and forming the passage for the branches, the bark of which is to be rossed, these belt members being here shown 45 as running over sets of sheaves 5, 5—6, 6 suitably supported by the frame, one set 5, 5 being arranged above the horizontal frame elements 1 and the other set 6, 6 below said elements. The lower sheaves 6, 6 are spaced 50 apart a greater distance than the upper sheaves 5, 5, so that the lower belt member projects beyond the upper. As seen in Fig. 3, the sheaves 5 or 6 at each end of the belt members 3 or 4, are preferably arranged 55 in a group of several units, but obviously, drums having grooved peripheries may be

used instead of the sheaves 5, 5—6, 6. The belt members 3, 4 are of substantial width and feed the branches endwise with their axes substantially parallel to the direction 60 of the feeding movement, and said belt members are provided with separated lengthwise sections the sections of the opposing portions of the belt members being arranged to engage the branches at three points. 65 Preferably the belt members consist of ropes running over the sheaves 5, 5 and 6, 6, the sheaves being grooved for receiving the sections or ropes. Although preferably a continuous rope passing several times around 70 the sheaves is employed for each belt member, obviously a plurality of such ropes may be employed, or a single continuous rope may be employed passing first around the sheaves 5, 5 and then around the sheaves 6, 75 6. Suitable spring pressed tighteners 7, 8 coact with the belt members 3, 4. The sheaves 5 and 6 are so arranged relatively to each other that portions of the belt members 3, 4 extending between the sheaves are 80 opposed to each other and form a passage for the branches, the bark of which is to be rossed, and also the sheaves are so arranged that the grooves of the sheaves 5 are arranged staggered with those of the sheaves 85 6 and thus the portions of the ropes on one side of the passage for the branches are arranged opposite to the interstices between the ropes of the belt member on the opposite side of said passage, so that the branches 90 are engaged simultaneously by three of the rope sections.

Suitable pressure means coöperate with the portions of the rope confining the passage, and as here shown, these pressure 95 means comprise a plurality of pairs of rolling parts, the units of each pair being arranged above and below the portions of the belt members confining the passage for the branches and on opposite sides of a plane 100 cutting said portions at a right angle, or in other words, out of vertical alinement.

Each of the upper rolling parts 9 extends full width of the belt members and is usually mounted on an axle 10 journaled in 105 fixed bearings 11 on the frame element 1. Each of the lower rolling parts 12 comprises a plurality of grooved sheaves, Fig. 4, one sheave for each rope, and each sheave is carried by one arm of an angle lever 13 mounted on the shaft 14 which is common to all the levers 13, and a spring 15 is connected 110

- to the other arm thereof. Usually, a plurality of such pressure means is employed, and in order that the opposed portions of the belt members confining the passage for the branches may have an undulating motion for the purpose of facilitating the rossing of the bark on the branches passing through said passage, the upper and lower rolling parts 9, 12 are so adjusted that the 10 distance between parallel planes tangent to the points of engagement of said opposed portions and said rolling parts 9, 10 of each pair is less than the combined thickness of said opposed portions.
- 15 For the purpose of adjusting one belt member relatively to the other, the axles 16 of the upper sheaves 5, 5 are journaled in boxes 17 adjustable along vertical guides 18 by means of vertical screws 19 supporting 20 the boxes. The guides 18 supporting one of the axles 16 for one group of the upper sheaves, as the front group, are adjustable lengthwise of the elements 1, by means of screws 20 journaled in the frame and extending through threaded eyes 21 provided on the guides. One group of the lower sheaves 6 is also adjustable toward and from the other group to take up the slack due to stretching of the rope, by means of screws 22 suitably supported in a bracket 23 depending from the frame element 1 and extending through a threaded collar 24 provided on the bearings for the axles 25 of said sheaves 6.
- 30 35 The means for removing the loosened bark from the branches after said branches have passed between the belt members consists of strippers 26 located at the exit end of the passage for such branches, such strippers 26 being composed of suitable yielding material of sufficient strength to strip the bark without scratching the naked branches.
- 40 Means is provided for drawing the branches out from between the belt members 3, 4 at a greater speed than they are carried by said belt members and thereby drawing them between the strippers at accelerated speed, and such means as here shown, comprises belt members 27, 28 similar in arrangement to the belt members 3, 4 and running over sheaves 29, 30 similar to the sheaves 5, 5—6, 6.
- 45 50 55 60 65 As before stated, the lower belt member 4 extends beyond the ends of the upper belt member 3 and such extension at the front of the machine forms a carrier on which the branches are placed and carried between the belt members 3, 4; and above such projecting portion of the lower belt member is provided means for guiding the branches between the belt members. Such guiding means consists of a deflector 32 extending crosswise of such projecting portion and spaced apart above the same, and a roller 33 in front of the deflector. Means is also

provided for breaking the bark prior to the entrance of the branches between the belt members 3, 4, such means being here shown as an abrading member 34 extending crosswise of the projecting portion of the lower belt member between the deflector 32 and the roller 33, such member having forwardly and downwardly extending fingers 35 which terminate between the sections or ropes of the lower belt member and prevent the 70 branches from entering the interstices between the ropes of the projecting portion and guide them over the abrading member. As the branches are fed onto such projecting portion of the lower belt member 4 the 75 advance ends thereof engage the fingers 35 and thus the branches are carried over the abrading member and their advance ends engage the deflector 32 and are directed between the belt members 3, 4, the branches being pressed on the abrading member by the roller 33. While they are being carried over said abrading member, the bark thereon is bruised and scraped but not sufficiently to remove it from the branches.

80 The sheaves 5, 6—6, 6 and 26 and 27 are actuated in any suitable manner and are here shown as connected to a main shaft 35 by power-transmitting means as a gear 37 mounted on the main shaft and meshing 95 with the gear 38 mounted on the axle of one of the sheaves 6, and with an intermediary gear 39 which in turn meshes with a gear 40 mounted on the axle of one of the upper sheaves 5. The motion is transmitted to 100 the sheaves 29 and 30 in order to rotate said sheaves in opposite directions by means of belts 41, 42.

105 In operation, the branches, the bark of which is to be rossed are placed on the projection portion of the lower belt member 4 and carried by said member over the abrading member 34 and under the deflector 32 and are then carried between the belt members 3, 4; and owing to the arrangement of 110 the sections or ropes of such belt members, such ropes engage each branch at three sides, and in passing through between the pressure rollers the bark is loosened on the branches. From between the belt members 3, 4 the 115 branches are passed through the strippers 26 and thence to the belt members 27 and 28, which are rotated at a greater speed than the belt members 3, 4 and therefore draw the branches at accelerated speed through 120 the strippers 26. Owing to the fact that the upper and lower pressure rolls are out of a vertical line the pressure of such rollers is not applied at diametrically opposite points of the branch and thus breaking or crushing 125 of the branch is avoided.

What I claim is:—

1. In a bark rossing machine, means for feeding the branches, comprising a belt member of substantial width consisting of 130

lengthwise separated sections supported and arranged side by side to support and feed the branches arranged parallel to the travel of the belt member, and sheaves supporting 5 the belt member, substantially as and for the purpose described.

2. In a bark rossing machine, means for feeding the branches comprising a belt member of substantial width consisting of ropes 10 arranged side by side to support and feed the branches arranged parallel to the travel of the belt member, and sheaves supporting the belt member, substantially as and for the purpose specified.

3. A bark rossing machine comprising belt members of substantial width having portions opposed to each other, and opposing portions therefor forming a passage for the branches, and arranged to support and 20 operating to feed the branches when the latter are arranged endwise with their axes substantially parallel to the direction of the feeding movement, sheaves supporting the belt members, and means for actuating the 25 belt members, substantially as and for the purpose set forth.

4. A bark rossing machine comprising belt members having portions opposed to each other and the space between said opposed 30 portions forming a passage for the branches and such belt members being of substantial width and composed of lengthwise separated sections arranged side by side in position to support and feed the branches when 35 the latter are arranged endwise with their axes substantially parallel to the travel of the belt members, sheaves supporting the belt members, and means for actuating the belt members, substantially as and for the 40 purpose specified.

5. A bark rossing machine comprising belt members having portions opposed and parallel to each other, the spaces between the opposed portions forming a passage for the 45 branches, and such belt members being of substantial width and composed of lengthwise separated sections arranged to support and feed the branches when the latter are arranged endwise with their axes substantially 50 parallel to the travel of the belt members, and means for actuating the belt members in opposite directions whereby the opposed portions thereof travel in the same direction, substantially as and for the purpose 55 set forth.

6. A bark rossing machine comprising belt members of substantial width, each consisting of ropes arranged side by side and forming lengthwise separated sections of said 60 belt member, portions of the belt members being opposed to each other and the spaces between said opposed portions forming a passage for the branches, the ropes being arranged to support and feed the branches 65 when the latter are arranged with their axes

parallel to the travel of the belt members, sheaves supporting the belt members, and means for actuating the belt members, substantially as and for the purpose described.

7. In a bark rossing machine, means for 70 engaging the branches, said means being of substantial width and comprising opposing members having separated engaging surfaces arranged to support and feed the branches when the latter are arranged endwise with their axes parallel to the direction of travel, the surfaces of one member being opposed to the spaces between the surfaces of the other member, whereby each branch is engaged at three points, substantially as and 80 for the purpose specified.

8. A bark rossing machine comprising belt members of substantial width provided with lengthwise separated sections, the belt members having portions opposed to each other, 85 and the belt members being so arranged relatively to each other that the sections of one of such members are opposed to the interstices between the sections of the other of such members, and the space between said 90 opposed portions of the belt members forming a passage for the branches, such opposed portions and the sections thereof being arranged to support and feed the branches when the latter are arranged endwise with 95 their lengthwise axes substantially parallel to the direction of travel of the belt members, and the separated sections engaging the branches at three points, sheaves supporting the belt members, and means for actuating the belt members in opposite directions, 100 substantially as and for the purpose set forth.

9. A bark rossing machine comprising belt members of substantial width consisting of 105 lengthwise separated sections composed of ropes, the belt members having portions opposed and parallel to each other, and the space between said belt members forming a passage for the branches, and the opposed 110 portions, and rope sections thereof being arranged to support and feed the branches when the latter are arranged endwise with their lengthwise axes parallel to the travel of the belt members, sheaves supporting the 115 belt members, the sheaves supporting one belt member being so arranged relatively to the sheaves supporting the other member, that the ropes of one of the opposed portions are arranged opposite to the interstices between the ropes of the other opposed portions, and means for actuating the belt members in opposite directions, substantially as 120 and for the purpose described.

10. A bark rossing machine comprising a 125 frame, a set of sheaves supported by the frame, a belt member running over the sheaves, a second set of sheaves supported by the frame, a belt member running over the same, the belt members being of substan- 130

tial width, the sets of sheaves being so arranged relatively to each other that portions of the belt members extending between the sheaves are opposed to each other, and are 5 arranged to support and feed the branches and the members of one set of sheaves being spaced apart a greater distance than the members of the other set of sheaves so that one of the belt members projects beyond the 10 other and the projecting portion thereof forms a table for receiving the branches to be fed between the belt members, and means for actuating the sets of sheaves in opposite directions, substantially as and for the purpose 15 specified.

11. A bark rossing machine comprising a frame, two sets of sheaves supported by the frame, belt members running over the sheaves, two sets of sheaves being so arranged 20 relatively to each other that portions of the belt members extending between the sheaves are opposed to each other, and the space between said opposed portions forming a passage for the branches, the bark of 25 which is to be rossed, means for actuating the sets of sheaves in opposite directions, and a pair of pressure elements acting on the opposed portions of the belt members confining said passage, the units of the pair 30 of pressure elements being located on opposite sides of a plane cutting said portions of the belt members at a right angle, substantially as and for the purpose described.

12. A bark rossing machine comprising 35 a frame, two sets of sheaves supported by the frame, belt members running over the sheaves, the sets of sheaves being so arranged relatively to each other that portions of the belt members extending between the sheaves are opposed to each other, the space between said opposed portions forming a passage for the branches, the bark of 40 which is to be rossed, means for actuating the sets of sheaves in opposite directions, and pressure means acting on the portions 45 of the belt members on opposite sides of the passage, said pressure means comprising a plurality of pairs of elements, the elements of each pair being located on opposite sides 50 of the portions of the belt members confining the passage, and on opposite sides of a plane cutting said portions at a right angle, and the distance between parallel planes tangent to the points of engagement of said 55 opposed portions and the pressure elements of each pair being less than the combined thickness of said opposed portions thereby causing said portions of the belt members confining the passage to have an undulating 60 motion, substantially as and for the purpose set forth.

13. A bark rossing machine comprising a frame, upper and lower sets of sheaves supported by the frame and rotatable about 65 horizontal axes, belt members running over

the sheaves, each bent member consisting of a plurality of lengthwise sections composed of ropes, and the sets of sheaves being so arranged relatively to each other that portions of the belt members extending between the sheaves are opposed to each other, and the space between the opposed portions forming a passage for the branches the bark of 70 which is to be rossed, pressure means arranged on opposite sides of the portions of the belt members confining the passage and on opposite sides of a plane cutting said portions at a right angle, the pressure means comprising a roller extending full width of the belt member and engaging one of said 75 belt members and a plurality of spring-pressed sheaves engaging the other belt member, one sheave for each rope of the latter belt member, and means for actuating the sets of sheaves in opposite directions, 80 substantially as and for the purpose specified.

14. A bark rossing machine comprising a frame, upper and lower sets of sheaves supported by the frame, belt members running 90 over the sheaves, the sheaves being movable about horizontal axes and the sets of sheaves being so arranged relatively to each other that portions of the belt members extending between the sheaves are opposed to each other, and the sheaves of the lower set being spaced apart a greater distance than the 95 sheaves of the upper set so that the lower belt member extends beyond the upper, means for actuating the sets of sheaves in 100 opposite directions, and means for deflecting between said belt members, branches on the projecting portion of the lower belt member, said means being located crosswise of said projecting portion of the lower belt 105 member and above the same, substantially as and for the purpose described.

15. A bark rossing machine comprising a frame, upper and lower sets of sheaves supported by the frame, belt members of substantial width running over the sheaves, the sheaves being movable about horizontal axes and the sets of the sheaves being so arranged relatively to each other that the portions of the belt members extending between the 110 sheaves are opposed to each other, and are arranged to support and feed the branches the sheaves of the lower set being spaced apart a greater distance than the sheaves of the upper set so that the lower belt member 115 extends beyond the upper, forming a table for supporting the branches prior to the passage thereof between the belt members, means for actuating the sets of sheaves in opposite directions, and an abrading member 120 extending crosswise of the projecting portion of the lower belt member, substantially as and for the purpose described.

16. A bark rossing machine comprising a frame, upper and lower sets of sheaves sup- 130

ported by the frame, belt members running over the sheaves, the sheaves being movable about horizontal axes and the sets of sheaves being so arranged relatively to each other 5 that portions of the belt members extending between the sheaves are opposed to each other, and the sheaves of the lower set being spaced apart a greater distance than the sheaves of the upper set, so that the lower 10 belt member extends beyond the upper, and the lower belt member including a plurality of lengthwise separated sections, means for actuating the sets of sheaves in opposite directions, and an abrading member extending crosswise of the projecting portion of the lower belt member, said member having forwardly and downwardly extending fingers projecting into the interstices between the sections of the lower belt 15 member, substantially as and for the purpose specified.

17. A bark rossing machine comprising a frame, upper and lower sets of sheaves supported by the frame, belt members running over the sheaves, the sheaves being movable about the horizontal axes and the sets of sheaves being so arranged relatively to each other that portions of the belt members extending between the sheaves are opposed 25 to each other, and the sheaves of the lower set being spaced apart a greater distance than the sheaves of the upper set so that the lower belt member extends beyond the upper, means for actuating the sets of 30 sheaves in opposite directions, means for guiding between said belt members, branches on the projecting portion of the lower belt member, said means being located crosswise of said projecting portion of the lower belt member 35 and above the same, an abrading member extending crosswise of the projecting portion of the lower belt member, in front of the guiding means, the abrading member consisting of a part having an abrading surface extending crosswise of the projecting portion of the lower belt member and fingers extending forwardly and downwardly into the interstices between the sections of the lower belt member, and a roller 40 extending crosswise of said projecting portion of the lower belt member in front of the abrading member, substantially as and for the purpose set forth.

18. A bark rossing machine comprising a frame, upper and lower sets of sheaves supported by the frame, belt members running over the sheaves, the sheaves being movable about horizontal axes and the sets of sheaves being so arranged relatively to each other 50 that portions of the belt members extending between the sheaves are opposed to each other, and the sheaves of the lower set being spaced apart a greater distance than the sheaves of the upper set so that the lower belt member extends beyond the upper, and the lower belt member including a plurality of lengthwise separated sections, means for actuating the sets of sheaves in opposite directions, means for guiding between said belt members, branches on the projecting portion of the lower belt member, said means being located crosswise of said projecting portion of the lower belt member 55 and above the same, an abrading member 60 extending crosswise of the projecting portion of the lower belt member, in front of the guiding means, the abrading member consisting of a part having an abrading surface extending crosswise of the projecting portion of the lower belt member and fingers extending forwardly and downwardly into the interstices between the sections of the lower belt member, and a roller 65 extending crosswise of said projecting portion of the lower belt member in front of the abrading member, substantially as and for the purpose set forth.

In testimony whereof, I have hereunto signed my name in the presence of two attesting witnesses, at Syracuse, in the county of Onondaga, and State of New York, this 12th day of February, 1910.

FREDERICK R. HAWLEY.
